UNITED STATES PATENT OFFICE

155,870

DESIGN FOR A BADGE OR SIMILAR ARTICLE

Franklin Brook and Stanley Wager, Long Island City, N. Y., assignors to Bob Franklin, Inc., New York, N. Y., a corporation of New York

Application May 15, 1948, Serial No. 146,398

Term of patent 3½ years

(Cl. D29—2)

To all whom it may concern:

Be it known that we, Franklin Brook and Stanley Wager, citizens of the United States of America, residing in Long Island City, in the county of Queens and State of New York, have invented a new, original, and ornamental Design for a Badge or Similar Article, of which the following is a specification, reference being had to the accompanying drawing, forming a part thereof, wherein:

Fig. 1 is a front elevation of a badge or similar article, showing our new design; and

Fig. 2 is a side elevation thereof.

The dominant feature of our design reside in the portion shown in full lines.

We claim:

The ornamental design for a badge or similar article, substantially as shown and described.

FRANKLIN BROOK.
STANLEY WAGER.
